UNITED STATES PATENT OFFICE

HERMANN BEHRENS, OF HANOVER, GERMANY, ASSIGNOR OF ONE-HALF TO MASCHINEN- UND WERKZEUGFABRIK KABEL VOGEL & SCHEMMANN A.-G., OF KABEL, GERMANY, A GERMAN COMPANY

MACHINE FOR TREATING GRANULAR MATERIAL

Application filed March 27, 1929, Serial No. 350,327, and in Germany October 11, 1927.

My invention relates to a machine for treating granular material and more particularly moulding sand, by means of which either moulding sand that has been used or moulding sand coming fresh from the pits 5 may be loosened and cleaned in order to get it ready for use.

The object of the invention is to provide a machine for the purpose stated, which 10 thoroughly exposes the sand to the air and at the same time consumes little power, is subject to but slight wear of the working parts, that owing to the construction of the machine are moreover not liable to break- 15 age, mechanically separates the impurities from the sand and is not liable to injure the attendants by the projection of solid par- 20 ticles. Moreover the supply of sand to the machine is easily effected in a simple man- 25 ner and the sand ready for use is discharged behind the machine, but not under it, so that the machine may be moved away without obstruction from the sand that has been treated and the sand may be removed with- 30 out hindrance from the machine.

The invention substantially comprises a 35 hopper, a drum rotating under the hopper, ledges presenting edges disposed parallel to the axis of the drum and a yieldingly 40 mounted throttling valve which forms with the periphery of the drum a passage that decreases in size in the direction of rotation of the drum.

Three constructions according to the 45 invention are illustrated by way of example in the accompanying drawing.

Figure 1 shows the machine in cross section.

Figure 2 is a longitudinal section on the 50 line A—B of Figure 1.

Figure 3 shows the main features of the machine diagrammatically in cross section.

Figure 4 is an elevation of the screening 55 device.

Figure 5 is a cross section of the screening device on the line C—D of Figure 1.

Figure 6 is a perspective view of the 60 throttling valve with its guide rods.

Figure 7 is a diagrammatic view similar 65

to Figure 3 but showing a modified shape of one feature.

Figure 8 shows a second construction of the machine in cross section.

Figure 9 is a longitudinal section of this 55 machine on the line E—F of Figure 8 and

Figure 10 shows an elevation of a third construction of the machine, similar to Figure 8, but stationary.

The spindle *u* of a drum *a*, Figure 1, sup- 60 ported in bearings *b* on the frame or bed *o*, is provided at its periphery with knives or ledges *c* presenting edges disposed parallel to its axis. There are preferably only a few 65 of these ledges, four being shown in the constructions illustrated, and from each ledge to the next extends a covering or lag- 70 ging plate or sheet *c'* which starts at the back of a ledge, close to its outer edge and terminates at the foot of the next ledge. The ends of the cover plates *c'* are secured 75 by means of strips *c''* that are disposed parallel to the ledges *c* and like the cover plates *c'* are fixed to the circular end plates *c³* of the drum *a*.

The drum *a* that is mounted on the bed 80 freely, viz without a casing, rotates in the direction of the arrow or clockwise and above the same and on the rising side of the drum as viewed in Figure 1 is mounted a hopper *d*, and adjacent to the hopper and between it and the vertical central line is pivotally mounted a throttling valve *e* that is carried by two rods *f* connected to the 85 valve by means of the brackets *e'*, Figure 6. The rods *f* are situated outside the hop- 90 per *d* and the brackets *e'* project through arc-shaped slots in the lateral walls of the hopper, the bearings of the rods *f* being secured to the rear wall. The throttling 95 valve *e* is formed as an angular plate and its main portion directed towards the hopper forms with the periphery of the drum *a* a passage that decreases in size in the direction of rotation of the drum, the other portion of the valve forming an obtuse angle with the main portion while stops *e''* limit the downward movements of the valve *e*.

The tangent *I* (Figure 3) to the circumfer- 100 ence of the drum at the point of discharge

from the hopper *d* strikes the lower surface of the throttling valve.

The lateral walls *k* of the hopper are extended beyond the bed *o* and carry adjacent to the machine two rakes constituted by straight wires *l* which are threaded at both ends on the rods *m* at regular intervals secured by distance pieces, the latter being arranged so as to permit each wire a slight lateral movement along the rods *m*. The two rakes are pivoted to the walls *k* by means of the upper rods *m* and they bear against ledges *n* mounted on the walls *k*, the wires *l* of one rake being arranged behind the intervals or gaps between the wires *l* of the other rake.

The walls *k* are connected together at the top by a plate *k'* that forms a roof and above which is mounted a shaking screen or sieve *h* carried on four vertical rods *q* that oscillate on two spindles *x* extending from one rod to the other on the bed *o* of the machine.

To oscillate the shaking screen *h* gear wheels *s* and *t* are employed the former of which is secured to the spindle *u* while the wheel *t* drives by means of a crank a connecting rod *r* that engages with one of the rods *q*. The bottom *i* of the shaking screen *h* is obliquely disposed so that the sand passing through the screen slides down into the hopper.

The bed *o* of the machine also supports an electric motor *v*, the shaft of which is arranged in line with the spindle *u* and is coupled to it by a coupling *v'*. The bed is provided with front wheels *p*, as shown in Figure 2, on which it may be supported, and with handles *p'* by which it may be propelled or, as shown in Figure 10, with legs so that it is stationary.

The drum *a* driven by the electric motor *v* rotates in the direction of the arrow shown in Figure 1 so that the sand discharged from the hopper *d* and cleaned in the shaking screen *h* is struck by the rotating ledges *c* and projected against the throttling valve *e*.

As a narrow passage is formed between the throttling valve and the passing ledges the sand will be rubbed by the ledges along the surface of the throttling valve which yields upwardly to allow the passage of large hard objects. Owing to the decreasing size of the passage between the throttling valve and the drum in the direction of rotation of the drum, the sand will be pressed by the throttling valve against the ledges of the drum so that they can strike and grind down the sand.

The sand flies freely through the air behind the throttling valve until it strikes the wires *l* of the first rake that keeps back large particles, more particularly iron particles, which fall down to the bottom. The coarse particles which have passed through one rake, are held up by the other rake on ac-

count of the relative staggering of the wires, the slight movement of the wires along the rods preventing sticking of the sand to the wires. Behind the two rakes which in this manner jointly form what may be regarded as an iron catcher, the sand falls down to the bottom and is then ready for use.

During this treatment of the sand lumps are broken up, the single sand particles are separated, exposed to the air and freed from foreign substances. The sand falling freely down is therefore loose and uniformly inter-penetrated by air-filled pores.

The depth of the knives or ledges *c* and the speed of rotation of the drum are inter-dependent in such a manner that the sand in the hopper *d* has time, between the passing of one ledge and the passing of the following one, to fall down almost to the end of a covering plate *c'*. Each knife or ledge therefore deals with a quantity of sand to almost its full depth and treats it in the manner described. This gives a circumferential speed of the drum of about 20 meters per second. The position of the throttling valve *e* relatively to the tangent *I*, Figure 3, prevents part of the sand from being forced back into the hopper. The outer edge of the knives or ledges is preferably smooth but they may also be serrated. The shape of the covering plates of the drum prevents the formation of air eddies behind the rotating knives or ledges.

In the construction according to Figure 7 the throttling valve *e* is formed integral with the lower part of the hopper *d* and both are mounted in the bearings *g* on the bed of the machine. The result of this is that the hopper *d* participates in the yielding movements of the throttling valve which tends to facilitate the discharge of the sand contained in the hopper and thereby ensure the smooth working of the subsequent operations.

In the construction according to Figures 8 and 9 the electric motor *y* is mounted in the interior of the drum *a* but it is not of the usual construction with the rotor inside but has an outside rotor *y'* and an inside stator *y''* that is rigidly secured to the fixed shaft *s* on which the drum rotates in ball bearings *b'* being secured to the rotor *y'*. The shaft *s* also carries the supporting wheels *p*. In this construction the whole machine is simplified and reduced in size and the shaking screen is dispensed with.

I claim:

1. A machine for treating granular material, comprising a hopper, a drum rotating under the hopper with radial ledges parallel to the axis of the drum and a yieldingly mounted throttling valve disposed above said drum which forms with the periphery of the drum a passage that decreases in size in the direction of rotation of the drum.

2. A machine according to claim 1, in which the hopper is situated above and on the rising side of the drum.

3. A machine according to claim 1, in which the number of ledges or knives are proportioned relatively to the circumferential speed of the drum so that the material to be treated falls during the passing of two ledges in front of the hopper into the space between the two ledges.

10 4. A machine according to claim 1, in which the covering plates of the drum start at the back of one ledge close to its outer edge and terminate at the foot of the next ledge.

15 5. A machine according to claim 1, in which the drum is mounted freely on the bed of the machine.

6. A machine according to claim 1, in which a motor with an inner stator and outer rotor is mounted in the interior of the drum in such a manner that the rotor of the motor is rigidly secured to the drum.

20 7. A machine according to claim 1, in which a shaking sieve or screen oscillated by the machine is mounted above the hopper.

25 8. A machine according to claim 1, in which an iron catcher constituted by several rakes with straight wires slightly movable along the rods on which they are threaded and staggered relatively to one another is situated in the path of the material treated by the drum.

30 9. A machine according to claim 1, in which the lower portion of the hopper is formed integral with the yieldingly mounted throttling valve.

35 In testimony whereof I have affixed my signature.

40 HERMANN BEHRENS.
